(57) **CLAIM**

The ornamental design for the toilet seat for aiding in the disposal of pet wastes, as shown and described.

DESCRIPTION

FIG. 1 is a front elevation view of a toilet seat for aiding the disposal of pet waste showing my new design;

FIG. 2 is a rear elevation view thereof;

FIG. 3 is a top plan view thereof;

FIG. 4 is a bottom plan view thereof;

FIG. 5 is a left side elevation view thereof; and,

FIG. 6 is a right side elevation view thereof.

The characteristic feature of the design resides in a top surface that has an engraved pattern of grooves so as to prevent pets from slipping.
